UNITED STATES PATENT OFFICE.

FREDERICK W. A. BROCKMILLER, OF ST. PETERSBURG, FLORIDA.

FAUCET FOR SODA FOUNTAINS.

1,427,148.

Specification of Letters Patent. Patented Aug. 29, 1922.

Application filed April 22, 1921. Serial No. 463,672.

To all whom it may concern:

Be it known that I, FREDERICK W. A. BROCKMILLER, a citizen of the United States, residing at St. Petersburg, in the county of Pinellas and State of Florida, have invented certain new and useful Improvements in Faucets for Soda Fountains, of which the following is a specification.

This invention relates to faucets for soda fountains and the primary object of the invention is to provide an improved faucet of simple and durable construction, which will function in a positive and expeditious manner, and in which there will be a minimum amount of wear upon the working parts, and which parts are freely accessible for repair when necessary.

Another object of the invention is to provide a faucet having a novel type of valve for controlling the flow of liquid through the faucet, and a novel means for operating the valve.

With these and other objects in view, the invention consists in the novel construction, arrangement and formation of parts, as will be hereinafter more specifically described, claimed and illustrated in the accompanying drawings, forming a part of this specification, in which drawings:

30 Figure 1 is a vertical longitudinal section through the improved faucet.

Figure 2 is a detail perspective view of the valve utilized for controlling the flow of liquid through the faucet.

35 Figure 3 is a front elevation of the faucet.

Figure 4 is a detailed vertical transverse section through the faucet, taken on the line 4—4 of Figure 1, the working parts being shown removed.

40 Figure 5 is an elevation of one of the side plates of the body of the faucet.

Referring to the drawings in detail, wherein similar reference characters designate corresponding parts throughout the several views, the letter A indicates the improved faucet, which includes the body B, the valve C, and the valve operating means D.

The body B may be of any preferred configuration and ornamented to suit the individual desires of the manufacturer, and is provided with a longitudinal way 10 forming the inlet to the faucet, and the vertical way 11 forming the outlet of the faucet.

55 The ways 10 and 11 communicate with a

central enlarged passage 12, which opens out at the opposite side of the body. Said opposite side of the body B has secured thereto the side plates 13, which cover the ends of the central passageway 12, and these side plates form means for supporting the pivot pins for the valve C and the operating means D as will be hereinafter more fully described. These side plates 13 conform to the configuration of the body B and are provided with suitable apertures 14 for the reception of fastening elements 15, by means of which the side plates are held in position. The way 10 has its bore enlarged, as at 16, and the enlarged portion of the bore receives the axial conduit pipe 17, which is arranged in spaced relation to the enlarged portion of the bore 16, forming an interior air chamber 18.

The inner end of the conduit pipe 17 may be threadably connected to the body as at 19. The opposite end of the conduit pipe may also be exteriorly threaded as at 20, so as to permit the same to be readily connected with the fluid line pipe (not shown). The inner end of the body may also be provided with exterior threads 21 for permitting the same to be readily threaded into position in the fountain, and can be provided with the usual ornamental sleeve 22, for hiding the point of connection of the faucet with the fountain. The provision of the dead air space 18 around the fluid conduit pipe 17 in the body B is a distinct improvement and this prevents the rapid cooling of that portion of the fluid which may be positioned in the body waiting to be dispensed. The inner end of the way 10 is provided with a valve seat, on which is adapted to fit the valve C, which will be now described.

95 The valve C is of the flap valve type and includes a flat body 23, of rectangular configuration having a hinged barrel 24 formed thereon adjacent to its upper end. The body 23 below the hinged barrel 24, is provided with a disc washer 25, which is adapted to seat on or cover the inner end of the longitudinally extending passageway 10, in order to prevent the flow of fluid therethrough. The inner surface of the body 23 above the hinged barrel 24 is curved transversely, as at 26, for a purpose which will be herein-after more fully described. The hinged barrel 24 is adapted to receive a transversely extending hinge pin 27, the terminals of

which are fitted in the side plates 13, and this hinge pin is located directly above the longitudinally extending passageway 10.

The operating means D comprising a lever 28 having a handle 29, which may be of an ornamental configuration formed on one end thereof, and an operating head 30 formed on its opposite end. This head 30 is of special construction and forms an important part of the invention and is extended into the central passageway 12. The inner end of the head 30 is provided with an arcuate cam face 31, which lies on the inner side of the transversely extending substantially semi-circular groove 32. The cam 31 is adapted to normally engage the transversely curved surface 26 of the body 23 of the valve C, and forms the operating member therefor. Directly above the cam end 31, the head 30 receives the pivot pin 33, which is in direct vertical alignment with the pivot pin 27 of the valve C, and this pivot pin 33 rockably supports the lever 28 and its head 30. The head 30 on the opposite side of the pivot pin 33 from the cam 31 has its lower surface provided with an arcuate face 35, against which is adapted to seat one end of a leaf spring 36. The opposite end of the leaf spring 36 is fitted within a suitable recess 37 formed in the passageway 12. By this construction, it can be seen that the spring 36 normally urges the cam end 31 into engagement with the body 23 of the valve and normally holds the valve on its seat, and absolutely precludes the escape of fluid through the longitudinal passageway 10.

When it is desired to operate the valve, it can be seen that it is merely necessary to pull down on the handle 29, which will rock the lever 28 and its head 30 on the pivot pin 33, and move the cam end 31 away from the curved surface 26 of the body 23 of the valve C, thus permitting the valve to be rocked on its pivot pin 27 under the influence of the pressure of the fluid. As the valve swings back, the same will form a guide for the fluid and direct the same down through the vertical passageway 11.

From the foregoing description, it can be seen that an exceptionally simple and durable faucet has been provided, for soda fountains, which merely embodies a body, a valve, and an operating lever for the valve.

If so desired the forward end of the body may be provided with a screw threaded extension 38 for receiving the carrier 39 for a lens 40, which can be utilized for protecting

a suitable label or the like, which can be positioned on the outer face of the screw 60 threaded extension 38.

Changes in details may be made without departing from the spirit or scope of this invention; but,

I claim:

1. A faucet comprising a body having a valve seat, a flap valve arranged to fit upon the seat including a body having a transversely extending hinged barrel arranged adjacent to its upper end, a pivot pin arranged through the barrel for supporting the valve, an operating member for the valve including a lever, a head formed on the lower end of the lever, a pivot pin extending through the head for rockably supporting the lever and head, a cam on said head arranged to engage the flap valve above the hinged barrel, and a leaf spring engaging the head on the opposite side thereof from the cam for normally holding the cam in engagement with the flap valve.

2. A faucet comprising a body having a valve seat, a flap valve arranged for cooperation with the seat including a flat body and a hinged barrel formed on the body adjacent to the upper end thereof, an operating member including a lever, and a head formed on the lower end of the lever, a pivot pin extending through the head for rockably supporting the head and lever, a cam formed on the inner end of the head arranged to engage the portion of the flap valve above the hinged barrel, a leaf spring engaging the head on the opposite side of the pivot pin from said cam for pressing said cam against said portion of the flap valve, the head and body having seats formed therein to receive the terminals of said spring.

3. A valve comprising a body having a longitudinally extending inlet passageway therein, and a vertically extending outlet passageway therein, and a central passageway opening through the side thereof, removable guide plates carried by the body on opposite sides of said central passageway and enclosing said central passageway, a flap valve carried by said guide plates and adapted to fit upon the inner end of the inlet passageway, and a lever extended into said central passageway through the side opening in the body and rockably supported by the guide plates arranged to engage said flap valve.

FREDERICK W. A. BROCKMILLER.
